MAGNETO FOR MODEL ENGINES

Emil Vollenweider, Sacramento, Calif.

Application August 7, 1939, Serial No. 288,803

9 Claims. (Cl. 123—149)

This invention relates in general to magneto ignition of gas engines, and in particular is directed to magneto ignition of extremely small or "midget" gas engines as are now available for use in connection with model airplanes, boats and the like.

Heretofore such model engines, due to the necessity for weight limitation, have been provided with a small battery and coil assembly to supply the requisite high tension ignition current. However, this type of ignition assembly is subject to the objection that the battery must be fresh in order to assure proper functioning of the engine, and to maintain a fresh battery requires frequent replacement with attendant cost and inconvenience.

It is therefore the principal object of this invention to provide a magneto for model engines which is proportionate in size and weight thereto, and also is of substantially no greater weight than the battery and coil assemblies as now used.

Another object of the invention is to provide—in combination with a model engine and driven therefrom—a magneto which is arranged so that the engine may revolve at speeds limited only by the characteristics of the engine.

A further object of the invention is to provide the combination of a model engine, a driving element (such as the propeller mounting hub of a model airplane), and a magneto interposed between the engine and element in connected and driven relation therewith.

It is also an object of the invention to provide a magneto for model airplane engines which is constructed and mounted with the engine in a manner to maintain proper balance of the engine.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Figure 1 is a side elevation of the magneto as mounted in connection with a model airplane engine.

Figure 2 is a cross-section on line 2—2 of Fig. 1 and looking forward therefrom.

Figure 3 is a front elevation of the magneto with the propeller hub partly broken away.

Figure 4 is an end view of the inductor rotor of the magneto.

Figure 5 is a longitudinal section on line 5—5 of Fig. 4.

Referring now more particularly to the characters of reference on the drawing, the magneto is shown in the present instance in combination with a model airplane engine of usual design, and including a cylinder 1, a fuel reservoir 2, a crankcase 3 formed with a projecting crankshaft bearing or boss 4, and a crankshaft having one end 5 extending through boss 4 and projecting some distance therebeyond as at 5a.

The magneto comprises a vertical back plate 6 having a central opening 7; a longitudinal split sleeve 8 being formed integral with the plate in register with opening 7 and projecting axially rearward. This split sleeve engages over the crankcase boss 4 and is clamped thereon by a clamping ring 9 including relatively long tightening screw 10 having a finger piece 11 on the outer end thereof. The plate 6 and sleeve 8 are of a non-magnetic metal such as brass.

The device includes an armature, of laminated silicon steel, having a core surrounded by an inductance coil 12, and field pieces 13 depending from the ends of the core at substantially right angles thereto; the inner edges of said field pieces defining the sides of an annular space in which the inductor rotor revolves as will hereinafter appear. The field pieces 13 are secured, by means of bolts 14, against the face of plate 6 with their arcuate inner edges concentric with the opening 7, and with the coil 12 in horizontal and uppermost position. The entire armature is thus fixed on the plate 6. The coil 12 includes, as usual, primary and secondary windings which are suitably insulated and disposed about the core between dielectric end plates 15.

The projecting portion 5a of the crankshaft extends through plate opening 7 and axially through the annular space between field pieces 13; said crankshaft portion 5a terminating some distance forwardly of the armature. The forward end of the crankshaft is cut with threads as at 16 and a nut 17 is threaded thereon.

An inductor rotor is mounted on crankshaft portion 5a for rotation between the field pieces 13. This rotor, as shown in detail in Figs. 4 and 5, comprises, as a unit, radially opposed pole shoes 18 of silicon steel, parallel magnets 19 extending between corresponding ends of the pole shoes, a substantially rectangular center section

or core 20 of non-magnetic metal, and vertical front and rear face plates 21 and 22 respectively of non-magnetic metal; said plates lapping over the outer edges of magnets 19 as at 23. The assembly is secured together by cross rivets 24. A hub 25 projects forwardly from the core 20 of the rotor, and the outer end of said hub being enlarged to form an annular propeller mounting flange 26. The rotor core 20, front face plate 21, hub 25, and flange 26 are formed integral.

The projecting portion 5a of the crankshaft extends axially through the rotor core 20 and hub 25, the rotor and crankshaft being secured against relative rotation by a squared shaft portion 27 seated in a square socket 28 in the rear end of the rotor.

The timing mechanism for the magneto comprises a supporting bracket 29 of non-magnetic metal mounted by bolts 14 above hub 25 and between the field pieces 13. One breaker point 30 is mounted on bracket 29 in insulated relation, while the cooperating breaker point 31 is carried on the adjacent end of a dielectric lever 32 pivoted intermediate its ends as at 33 on bracket 29 and actuated at the other end by a cam 34 on hub 25. As is obvious, the points make and break with rotation of the rotor and the included hub 25. A leaf spring 35 is fixed with the lever and point 31 and arranged so as to engage a stop 36 under tension and so as to urge the normally open points together; this spring also serving as a ground lead.

The high tension lead 37 of coil 12 is connected with the spark plug P of the engine, while one primary lead 38 is connected with the fixed point 30, and the other primary lead 39 is grounded on the adjacent field piece.

The above described magneto needs no condenser connected between the points due probably to the small size of coil 12; an inherent capacity being created which does away with the necessity of a condenser. As no condenser is used, the magneto functions properly at very high speeds and which could not occur if a condenser were used as the charging and discharging thereof limits the speed at which a magneto can function. A model engine with my magneto as the ignition source can revolve at speeds much in excess of similar engines with battery ignition.

In use, the propeller (not shown) fits on crankshaft portion 5a and abuts against flange 26; the nut 17 holding the propeller securely in engagement with said flange. With actuation of the engine, the magneto rotor and propeller rotate at the same speed; rotation of said magneto rotor producing the ignition current.

The magneto is light in weight, is positioned so as to maintain proper balance of the engine, and produces a positive and intense spark. Advancing or retarding of the spark is accomplished by merely unloosening screw 18 and rotating the entire magneto in one direction or the other about the crankcase boss 4; such movement varying the relative position of engagement of cam 34 and lever 32.

In order to provide proper lubrication of cam 34, the rotor is formed with openings 40 parallel to the axis thereof and in which openings wicks 41 are disposed. Oil from within the crankcase feeds out slowly between the crankshaft 5 and boss 4 onto the adjacent ends of said wicks and thence is fed to the other ends of the wicks and out to the cam.

From the foregoing description it will be readily

seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A magneto structure for direct drive by the crankshaft of an engine, said engine having a crankcase provided with an exterior boss surrounding the crankshaft, and beyond which the latter projects; a supporting member adjacent the outer end of the boss, a sleeve on said member engaging and secured on the boss, a non-rotatable magneto unit mounted on and supported by said member and including opposed field pieces and a magneto rotor fixed on the projecting portion of the crankshaft between the field pieces.

2. A magneto structure for direct drive by the crankshaft of an engine, said engine having a crankcase provided with an exterior boss surrounding the crankshaft and beyond which the latter projects, a member surrounding and turnable on the boss, a stationary magneto unit including opposed field pieces supported by said member, a magneto rotor fixed on the projecting portion of the crankshaft between the field pieces and means applied to the sleeve to adjustably hold the same against rotation on the boss.

3. A magneto structure for direct drive by the crankshaft of an engine, said engine having a crankcase provided with an exterior boss surrounding the crankshaft and beyond which the latter projects; a radial supporting plate having a rearwardly extending sleeve into which the boss projects, a magneto part mounted on the plate, a cooperating part mounted on and driven by the projecting portion of the crankshaft, and means securing the sleeve on the boss.

4. A magneto structure for direct drive by the crankshaft of an engine, said engine having a crankcase provided with an exterior boss surrounding the crankshaft and beyond which the latter projects; a radial supporting plate having a rearwardly extending sleeve turnably engaging the boss, a magneto part mounted on the plate, a cooperating magneto part mounted on and driven by the projecting portion of the crankshaft, and a clamping collar surrounding the sleeve, the latter being split longitudinally under the collar.

5. A magneto structure for direct drive by the crankshaft of an engine, said engine having a crankcase from which the crankshaft projects, a stationary magneto unit including opposed field pieces fixed with the crankcase, a rotor fixed on the projecting portion of the shaft to cooperate with said field pieces, a make and break ignition control device supported on said unit, a hub on the rotor projecting axially therefrom, and a cam on said hub to actuate the device.

6. In an engine driven magneto, a drive shaft, a boss in which said shaft is journaled and beyond the outer end of which the shaft projects, the inner end of the boss being exposed to a lubricant for the journaled portion of the shaft, a magneto rotor fixed on the shaft beyond the boss, a make and break ignition control device beyond the rotor, a cam fixed with the rotor to

actuate said device and means to feed the lubricant from the outer end of the boss past the rotor and onto the cam.

7. In an engine driven magneto, a drive shaft, a boss in which said shaft is journaled and beyond the outer end of which the shaft projects, the inner end of the boss being exposed to a lubricant for the journaled portion of the shaft, a magneto rotor fixed on the shaft beyond but immediately adjacent the boss, the portion of the shaft on which the rotor is mounted being reduced in diameter, a make and break ignition control device mounted adjacent and beyond the rotor, a cam fixed with the rotor to actuate the device, the rotor having a passage therethrough from end to end and whose radially inner edge

is substantially aligned with the bore of the boss, and a wick in said passage.

8. In the combination of a model airplane engine and an engine actuated magneto, said engine having a crankcase and a crankshaft projecting at one end from the crankcase and having an outer end portion adapted for connection with a propeller; said magneto including an inductor rotor secured on the projecting portion of the shaft between the crankcase and said outer end portion of the shaft.

9. A device as in claim 8, with a hub on the shaft rigid with and projecting forwardly from the rotor and having an enlarged propeller engaging flange on its forward end.

EMIL VOLLENWEIDER.
